CLAIM

The ornamental design for an intermediate horizontal ledge on furniture, as shown and described.

DESCRIPTION

FIG. 1 is a front perspective view of the intermediate horizontal ledge on furniture of the present invention showing my new design with the dotted lines depicting environmental structure and forming no part of the claimed design;
FIG. 2 is a top plan view thereof;
FIG. 3 is a front elevational view thereof; and,
FIG. 4 is an end view thereof.
